UNITED STATES PATENT OFFICE.

ANTON HERZINGER, OF PLAINVIEW, NEBRASKA.

WATER-HEATER.

1,159,221.

Specification of Letters Patent.

Patented Nov. 2, 1915.

Application filed February 15, 1915. Serial No. 8,391.

To all whom it may concern:

Be it known that I, ANTON HERZINGER, a citizen of the United States, residing at Plainview, in the county of Pierce and State 5 of Nebraska, have invented certain new and useful Improvements in Water-Heaters; and I do hereby declare the following to be a full, clear, and exact description of the invention, such as will enable others skilled 10 in the art to which it appertains to make and use the same.

This invention relates to water heaters, designed more particularly for heating water for stock in cold weather, and one of 15 the principal objects of the invention is to provide a heater of simple construction which will require but little attention and which will keep the water in circulation through service pipes.

20 Another object of the invention is to provide a heater of simple construction surrounded by a water jacket and having a series of pipes connected to the water jacket and leading out through various places 25 where it is desired to use the water, and having a pipe connection leading from a suitable source of supply for water, so that the water can be kept in circulation and in proper condition for use in watering stock.

30 The foregoing and other objects may be attained by means of the construction illustrated in the accompanying drawing, in which—

Figure 1 is a vertical sectional view taken 35 through a water heater made in accordance with this invention, and Fig. 2 is a horizontal sectional view of the same.

Referring to the drawing, the numeral 1 40 designates a drum which is preferably open at the bottom as at 2 and provided with a cover 3, said cover having ventilating openings 4 therein, and air pipes 5 leading from near the lower end of the drum up through the top or cover 3, said air pipes being disposed at each corner of the drum.

45 A water container 6 of circular form having its inner walls flaring, as shown at 7, and contracted at the upper end to form an opening, has connected to it at three different points pipes 8 which communicate with the interior of the water container.

A deflector 9 is mounted on legs 10 and

secured at the upper side of the water container immediately above the opening at the top of the flaring walls 7.

55 A coiled and perforated burner 11 having jet openings 12 therein is disposed immediately underneath the water container, and said burner is supplied by gasolene or other fuel through the pipe 13 which leads up 60 through the drum 1 and is provided with a tank 14 containing the fuel. A valve 15 is used to feed the fuel down to the burner, and a stop valve 16 is used at the burner to regulate the flame.

65 The air pipes 5 being open at their upper ends, and their lower ends terminating above the lower edge of the drum 1, air will be drawn in through the bottom of these pipes to support the flame at the burner. The 70 heated air, which is deflected by the deflector 9, gradually passes out through the opening 4.

75 From the foregoing it will be obvious that the water in the container 6 may be heated in a short time and discharge through the pipe to the point where it is to be used for watering the stock, and that the deflector 9 retards the heat and thus economizes in the use of fuel.

80 Various changes may be made in the details of construction without departing from the spirit and scope of the invention as defined in the claim.

85 What is claimed is—

A water heater comprising a drum, a closure at one end of the drum, said closure having outlet openings therein and an inlet opening near each corner, pipes secured in said inlet openings and extending into said 90 drum and terminating at a point in close proximity to the edge of said drum, a burner in said drum, a fuel tank secured externally of said drum, a feed pipe extending into said drum and connecting the tank to the 95 burner, and a water receptacle over said burner.

In testimony whereof I affix my signature in presence of two witnesses.

ANTON HERZINGER.
